WINDOW DEVICE

Joseph B. Clay and Walter O. Wille, Cedar Falls,
Iowa, assignors to Clay Equipment Corpora-
tion, Cedar Falls, Iowa

Application February 26, 1932. Serial No. 595,274

2 Claims. (Cl. 189—69)

Our invention relates to improvements in window devices, and the objects of our improvements are, first, to provide a ventilating window for stock barns and other building structures, 5 whose hinged sash is mounted and partially inclosed to suitably and adjustably admit fresh air in a desired direction into the interior of the building, and by the employment of inexpensive means adapted for easy and convenient 10 operation. Second, we have furnished a special locking mechanism to secure the sash in a closed, or in any opened adjusted position, comprising two devices which have each their own peculiar and distinct functions, yet practically 15 cooperate together by the use of a single operating rock-arm, and which also include means for forcing the sash open by the same movement which releases the sash. While our invention is particularly appropriate for use in barns or 20 houses for animals or fowls, it may be employed elsewhere, and various modifications may be made in its details without departing from the invention, or the protection of our claims.

We have successfully accomplished the reduction of this invention to practice, by the means which are hereinafter described and claimed, and which are illustrated in the accompanying drawing, in which Fig. 1 is a front elevation of our window device as seen from the 30 interior of a building looking outwardly, the device being closed. Fig. 2 is a side elevation thereof with parts broken away. Fig. 3 is a top plan thereof. Figs. 4 and 5, on a larger scale, are perspective details of the sash locking means, 35 respectively closed and open, or unlocked. Fig. 6 is a perspective detail showing the initial position of one of the friction clutching devices for a wing, associated with the locking means, to adjustably secure the sash to the wings in 40 different open positions. Fig. 7 is an elevation of the catch for the locking rock-arm. Fig. 8 is a detail view of a part of the hinged locking mechanism.

1 denotes a metal window frame having jambs 45 connected by end members 1a and 1b, and may be mounted in a suitable wall opening. Angle plates 2 thereon, with screw-bolt and slot adjusting means at 3 and 4, may be used to secure the frame between bricks or tiles of the wall 50 therearound.

The numeral 5 denotes a window sash of metal 55 preferably, having panes 6, but may have one or more, secured by putty or other means, and the frame has an upwardly flanged sill member 1b to rockingly seat the lower and inserted end of

said sash, a hooked handle 7 on the sash being provided for handling it. When closed thereagainst, the sash is snugly fitted therein, so that when locked thereto prevents passage of air therebetween, and the lower bar of the sash 50 has welded therealong and angle-bar drip-cap 22 to divert moisture from inner face of sash across the part 1b.

The numeral 16 denotes a like pair of transversely spaced and substantially triangular side 65 wings, imperforate, and with upper edges somewhat convex and of practically the same radial lengths as the sash 5. The forward inclined edges of the sash are bent inwardly toward each other at 17 to serve as stops for the sash 5 when 70 swung open to its full extent. Each wing 16 has at a distance below its top a cross rib or crimp 18 to serve as a contacting bearing for the adjacent wall or jamb of the sash, and also stiffens the wing. The lower diminished end 75 parts of the wings 16 are seated between the spaced flanges of the sill member 1b. The rear marginal parts of the wings are secured to the frame jambs by said screw-bolts 3 and nuts.

The upper cross member 1a of the frame has a 80 medial forward and terminally downturned member 8. On the ends of the upper sash bar are fixed apertured bearing lugs 12 seating therethrough a rock-shaft 13 whose middle part is also mounted rockingly in a spaced pair of 85 apertured lugs 11 on the sash bar. A plate element 9 is fixed on said shaft between the lugs 11 and has an offset outer terminal 9a to be limited in one direction of movement by a fixed lug 21 on the sash between the lugs 11. A plate 90 element 10 is fixed upon the element 9 and has a bent over termination 10a. When the device is locked, as in Fig. 8, this termination is flush with the frame member 1a. When the plate 10 is rocked as in Fig. 5, the termination 10a contacts with the part 8 and acts against it as a 95 cam, with pressure action between the same which slightly separates the sash and frame forcibly, to break any adhesion by ice therebetween, as it is difficult to do without this appliance and its cam action.

The numeral 20 denotes a medially bent handle 105 rod with spaced members whose terminations are fixed to and under the plate element 9, and a forked catch 19 on the sash 5 has undercut furcations at 19a and 19b to receive the members of said handle in the recesses 19b to secure them thereto releasably, when the said members are compressed slightly together to pass between the 110

furcations and react into the recesses when released.

The end parts of the rock shaft 13 are bent at an angle thereto and then shaped spirally at 14 at less than one turn, and have their terminals flattened at 15 wedge-shaped to narrow them. Near their bends the parts 14 cross the upper edges of the wings 16 so that the spiral parts are without the wings, the terminations 15 clearing 10 the wings to permit free rocking and other movements of the spirals along the wings, but when the rock shaft is rocked in one direction by the handle 20, the crossing parts of the shaft at the bends engage and frictionally lock with the wings to 15 hold the sash, as indicated by the dotted line in Fig. 1, to the wings as against accidental displacement therefrom. In this position, the handle 20 is to be engaged with the furcations of the catch 19 as above described, effecting a lock for 20 the sash in the adjusted open position. To release the sash, the handle 20 is disengaged from said catch 19, and swung from it to rock the shaft 13 enough to release the locking engagements of 25 the spirals 14 upon the wings 16, and the sash when swung to a closed position, may be locked against the frame with its member 9a under and stopped by the frame member 8 as shown in Fig. 8, and the handle re-locked with the catch 19 as described. Lugs 16a on the flanges 17 of the 30 wings and other lugs 5a on the sash coact in holding the sash and wings when the sash is tilted and raised.

In case the sash when locked becomes adherent to the frame 1 by ice cementation, the handle 20 is to be disengaged from the catch 19, swung up, and the cam end 10a of the plate 10 thrust against the frame member 8, thus forcibly separating the sash from the frame in breaking the cementation. This result is attained without interfering with any clutching or locking operations. 80

Having described our invention, what we claim as new, and desire to secure by Letters Patent, is: 85

1. In a window device, in combination, an open window frame including side wings, a sash mounted swingably in said frame between the wings, and a rock-shaft mounted upon an end of the sash to extend at its ends across the wings and having terminals spirally shaped in open loops to be unengaged in one position with the wings, and in other adjusted positions to be frictionally engaged with the wings to releasably latch the sash to the wings. 90

2. In a window device, in combination, an open window frame including side wings, a sash mounted swingably in said frame between the wings, and a rock-shaft mounted upon an end of the sash to extend at its ends across the wings and having terminals bent over and beveled to be at times in frictional contact with the outer walls of the wings to latch the sash to the wings in any of desired positions of swinging away from said frame. 100
